GARMENT DISPLAY POCKET

Filed Oct. 2, 1952

UNITED STATES PATENT OFFICE

2,671,902

GARMENT DISPLAY POCKET

Louis F. Grue, Baltimore, Md.

Application October 2, 1952, Serial No. 312,712

1. Claim. (Cl. 2—247)

1

This invention relates to garments and particularly jackets, coats or shirts having patch pockets, and in particular a patch pocket having an opening through the outer wall with an intermediate partition on the inside of the material forming the wall of the pocket forming a small auxiliary pocket, whereby an emblem, article, or other piece of material in the auxiliary pocket is displayed through the opening in the wall of the pocket and is separated from the body portion of the pocket in which a handkerchief or other article may be positioned.

The purpose of this invention is to provide means for displaying insignia such as used by servicemen, clubs and other organizations without permanently attaching, such as by stitching the insignia to the garment, thereby making it possible to readily remove the insignia when the garment is changed or when the garment is washed or cleaned.

Various organizations require that emblems or other insignia be attached by stitching to different parts of garments and when the garment is changed or washed or cleaned it is necessary to remove the emblem or other insignia from one garment and attach it to another. With this thought in mind this invention contemplates a comparatively small auxiliary pocket preferably formed against the inner surface of the outer wall of a pocket whereby an insignia or emblem positioned in the auxiliary pocket may be displayed through an opening in the outer wall of the pocket.

The object of this invention is, therefore, to provide means for displaying emblems or other insignia through the wall of a pocket of a garment.

Another object of the invention is to provide insignia displaying means in a pocket of a garment without interfering with the conventional use of the pocket.

A further object of the invention is to provide a garment having insignia or emblem displaying means in a pocket thereof in which the garment is of a simple and economical construction.

With these and other objects and advantages in view the invention embodies a piece of material adapted to form the outer wall of a pocket, preferably of the patch pocket type in which a layer of material is stitched to the inner surface of the wall of the pocket forming a comparatively small auxiliary pocket and in which the piece of material forming the wall of the pocket is provided with an opening for displaying objects in said auxiliary pocket.

2

Other features and advantages of the invention will appear from the following description taken in connection with the drawing, wherein:

Figure 1 is a front elevational view illustrating the improved emblem or insignia displaying pocket showing the pocket on the outer surface of a garment and with parts of the garment broken away.

Figure 2 is a vertical section through the pocket and adjoining portion of the garment taken on line 2—2 of Fig. 1.

Figure 3 is a sectional plan through the garment with the pocket on the outer face thereof taken on line 3—3 of Fig. 1.

Figure 4 is a detail showing an exploded view wherein the insert on which the emblem or insignia is positioned is withdrawn from the auxiliary pocket.

Figure 5 is an elevational view looking toward the inner surface of the outer wall of the pocket and showing the auxiliary pocket stitched to the outer wall of the pocket.

Figure 6 is a detail showing another exploded view wherein an insert in the form of a layer of material is withdrawn from an auxiliary pocket on the inner surface of the outer wall of a pocket.

Referring now to the drawing wherein like reference characters denote corresponding parts the improved display pocket of this invention includes an outer wall 10 having an opening 11 therein and an inner panel or layer of material 12 positioned on the inner surface of the outer wall.

The outer wall or panel 10 with the inner panel 12 on the inner surface and with the upper end of the panel 12 open forms a small auxiliary pocket and an emblem, as indicated by the numeral 14 may be inserted in the inner or auxiliary pocket formed by the panel 12 whereby the outer face of the emblem 14 is displayed through the opening 11 in the outer wall or panel 10.

It will be understood that the large pocket and also the auxiliary or small pocket may be formed by suitable means however, in the design shown the outer panel or wall 10 is provided with a lining 15 and the side and lower edges of the panel are turned, as illustrated in Figs. 2 and 3 whereby the edges are stitched to a wall 16 of a garment by stitches 17. By the same means an inturned edge 18 is provided around the opening 11 with said inturned edge stitched to the adjoining edge of the lining 15. In this design the side and lower edges, as indicated by the nu-

meral 19, of the small panel 12 are secured to the lining 15 by stitches 20 whereby in normal use the panel 12 will be pressed snugly against the inner surface of the outer wall of the pocket and the body of the pocket is adapted to be used for a handkerchief or other articles in the usual manner. The thickness of the materials is exaggerated for the purpose of illustration in Fig. 3, however, it will be understood that the comparatively thin panel 12 will be nested against the inner surface of the wall 10 so that it will not interfere with regular use of the pocket.

In the design shown the upper edge of the outer wall 10 of the pocket is also turned inwardly providing an inturned strip 21 which is secured to the upper edge of the lining 15 with stitches 22. The panel 12 may also be provided with an inturned upper edge 23 if desired.

With the parts formed in this manner an emblem, insignia, or a layer of material of a color different from that of the garment or outer wall of the pocket may be placed in the auxiliary pocket whereby it will be displayed through the opening 11 in the outer wall 10 and this piece of material, emblem, or the like may be withdrawn and replaced or otherwise changed as may be desired.

It will be understood that modifications, within the scope of the appended claim, may be made in the design and arrangement of the device without departing from the spirit of the invention.

What is claimed is:

In combination with a garment, a first piece of material shaped to form the outer wall of a patch pocket and stitched on the bottom and side edges thereof to the outer surface of the gar-

ment, a second piece of material substantially coextensive with said first piece of material stitched to the inner surface of said first piece of material with the same stitches which secures the first piece of material to the garment, said second piece of material providing a lining covering the inner surface of the first piece of material, a third piece of material of smaller size than said first and second pieces of material positioned against the inner surface of said second piece of material and stitched to said second piece of material to provide an auxiliary pocket which is positioned approximately at the center of said first and second pieces of material, said first and second pieces of material having an opening extending therethrough approximately at the center thereof, and said opening being of smaller size than the third piece of material, and said auxiliary pocket being adapted to receive display objects positioned therein so that said objects are visible through the opening in the said first and second pieces of material and said objects being larger than the opening, but smaller than the auxiliary pocket so that said objects are maintained in fixed relation to the openings in said first and second pieces of material.

LOUIS F. GRUE.
